TRAFFIC SIGNAL

Application filed December 18, 1922. Serial No. 607,611.

This invention relates to a traffic signal adapted to be placed at street crossings of cities and other places where the traffic of vehicles and pedestrians is more or less congested, the main object being to control the traffic and thereby to avoid the dangers incidental thereto.

It is well known that in most cities and villages the traffic along certain streets or thoroughfares is considerably heavier than that along other cross streets, and this traffic varies materially at different periods of the day and night, under which conditions it is obviously necessary to vary the "Stop" and "Go" periods on one or both of the crossing streets according to the amount of traffic without imposing undue delays on the traveling public, and one of the essential objects of this invention is to render the operation of the "Stop" and "Go" signals entirely automatic and variable as to their time periods of presentation according to the condition of the traffic so that the device may be set to give time periods for the traffic along the more congested street and different time periods for the traffic along the cross street.

Other objects and uses relating to specific parts of the apparatus will be brought out in the following description.

In the drawings, Figure 1 is a side elevation of a traffic signal embodying the various features of our invention, the central portion of the upright standard being broken away.

Figure 2 is an enlarged horizontal sectional view taken on line 2—2, Figure 1.

Figure 3 is a vertical sectional view taken in the plane of line 3—3, Figure 2.

Figure 4 is an enlarged vertical sectional view of the upper portion of the device taken on line 4—4, Figure 1.

Figure 5 is a vertical sectional view taken in the plane of line 5—5, Figure 4.

Figure 6 is an enlarged horizontal sectional view taken on line 6—6, Figure 1.

Figure 7 is a horizontal sectional view taken in the plane of line 7—7, Figure 5.

Figure 8 is a horizontal sectional view taken on line 8—8, Figure 1.

Figure 9 is a diagrammatic view of the

several lamp and bell circuits of the signal together with the switches for controlling said circuits.

Figure 10 is a detail sectional view taken in the plane of line 10—10, Figure 4.

Figure 11 is a perspective view of the detached commutator sleeve.

As illustrated, this traffic signalling device comprises a stationary upright frame having a supporting base or pedestal —1—, a tubular post or column —2— secured at its lower end to the base or pedestal —1— and carrying at its upper end, a case or housing —3— which together with the pedestal —1— and column —2— contain the various working parts and protects them from the elements, and also from accidental or malicious interference by unauthorized persons.

The upper reduced portion of the base or pedestal —1— preferably consists of a four-sided hollow pyramid containing a plurality of, in this instance eight, incandescent electric lamps —R— and —G—, arranged in sets of two, one set for each side and each set consisting of a red lamp —R— and a green lamp —G— both of which are visible through a transparent lens —5— in the corresponding side of the pedestal as indicated in Figures 1 and 8 and diagrammatically, in Figure 9.

The base or pedestal —1— may be permanently installed upon a suitable foundation at a street crossing with two of its opposite lenses —5— facing in opposite directions along one street and the other two facing in opposite directions along the crossing street so that they may be visible by vehicle drivers and pedestrians at either side on both streets.

The column —2— is permanently secured at its lower end to the pedestal —1— and extends upwardly any suitable height preferably sufficient to support the case —3— above the level of the tops of street cars and other vehicles so that the signals carried in said case may be, at all times, visible by pedestrians and drivers of approaching machines, said column being provided at a suitable height with an opening normally closed by a key-locked door —4— permitting access to certain manually controlled parts hereinafter described.

The case —3— is preferably square in horizontal section and its four sides arranged to correspond to the four sides of the pedestal —1— and provided with similar relatively large circular dials —6— which are graduated circumferentially and mounted in circular door frames —7— capable of being removed when necessary but normally locked in their closed positions to permit authorized access 10 to the interior mechanisms when desired, said dials being preferably made of clear transparent material such as glass, while the graduations may represent intervals of time such as fractions of a minute.

15 One or more sides of the portion of the case below the dials —6— may be provided with openings which are normally closed by key-controlled doors —8— to further permit authorized access to the interior mechanisms 20 for repairs, replacements or adjustments.

The side walls of the case —3— are preferably made up as a unit which is removably secured at its lower end upon a bottom plate —9— having a central downwardly projecting boss or hub —10— which in turn is secured telescopically upon the upper end of the column —2—, the upper end of the case being normally closed by a conical top —11— removably secured thereto in any suitable 30 manner.

The portions of the side walls of the case registering with the dials —6— are depressed inwardly toward the center to form similar conical reflectors —12— and similar chambers —13— between the dials and reflectors for a purpose presently described.

Each chamber contains a set of two incandescent electric lamps —R— and —G— which are secured in opposed relation to 40 opposite walls of the reflector —12— preferably one above the other and have their bulbs made of glass or equivalent transparent or translucent material, colored respectively red and green, and like the similarly colored sets 45 of bulbs in the pedestal —1— constitute what may be termed "Stop" and "Go" signals.

Suitable means is provided for automatically energizing these signals at regular predetermined intervals of time whereby the 50 "Stop" signals in opposite sides of both the pedestal —1— and case —3— and two of the "Go" signals in the remaining opposite sides of the pedestal and case will be simultaneously energized for a certain period of time, while the remaining signals will be de-energized, and at the end of that period of time, the signals previously energized will be de-energized and the remaining signals energized for the same or for a different period 60 of time as will be hereinafter more fully explained.

An electric bell —14— is suitably mounted in the upper portion of the case —3— and is adapted to be energized for a short interval 65 of time to give an audible signal during the

change of visual signals about to be made so that traffic may be prepared to "Stop" or "Go" as directed by the visual signals.

Suitable pointers or index fingers —15— are moved around the dials —6— within the 70 corresponding chambers —13— and for this purpose are mounted upon the outer ends of separate horizontal shafts or spindles —16— which are journaled in bearings —17— at the centers of the conical reflectors —12— to radiate from the center of the case coaxially with their respective dials —6— and in order that they may be visible at night, each pointer carries near its outer end, a relatively small electric incandescent lamp 80 —18— all of which are connected in the lighting circuits hereinafter described.

A constant speed electric motor —19— is suitably mounted within the case —3— preferably upon the bottom plate thereof and has its armature shaft —20— provided with a worm —21— meshing with a worm gear —22— which in turn is secured to a horizontal shaft —23— at right angles to the motor shaft —20—.

The shaft —23— is journaled in suitable bearings —24— within the case —3— and is provided with a pinion —25— meshing with a relatively large spur gear —26— which in turn is formed from the periphery of a friction disk —27—, Figure 4.

The friction disk —27— is mounted upon a supporting shaft —28— which in turn is journaled at its ends in suitable bearings —29— within the case —3— to rotate about a horizontal axis parallel with the shaft —23—.

A pair of upright tubular shafts —30— and —31— are journaled at their lower ends on end thrust bearings —32— at opposite sides of the friction disk —27— and have their upper ends journaled respectively in bearings —33— and —34— within the case —3—, said shafts being provided with similar intermeshing gears —35— for transmitting rotary motion from one to the other and are also provided with axially movable friction disks —36— and —36'— for frictionally engaging opposite faces of the disk —27— and thereby transmitting rotary motion from said disk —27— to the shafts —30— and —31—.

The shaft —30— is coaxial with the column —2— and extends upwardly along the center of the case —3— and is provided at its upper end with a beveled gear —37— which meshes with beveled pinions —38— on the inner ends of the pointer shafts —16—, the ratio of the gear and pinions being two to one so as to rotate the pointers at twice the speed of the tubular shafts —30— and —31—.

The speed of rotation of the disk —27— is constant, but greatly reduced from that of the motor by the reason of the reducing ratio

between the worm —21— and gear —22— and the further reducing ratio between the pinion —25— and gear —26— on the disk —27—, but by moving the disk —36— axially or radially along the adjacent face of the disk —27— the speed of rotation of the shaft —30— and pointer —15— driven thereby through the medium of the beveled gears —37— and —38— may be varied to increase or decrease the time interval of each complete revolution of the pointers from their zero or starting positions, and return.

The axes of the tubular shafts —30— and —31— are parallel and equal distances from opposite sides of the disk —27—, which sides are also parallel with the axes of the shafts and permit the driven disks —36— and —36'— to be moved axially parallel with said sides for varying the speed of rotation of the pointers relatively to the driving disk —27—.

For example, if both disks —36— and —36'— were set at the same distance from the axis of the disk —27— their corresponding shafts —30— and —31— would, of course, be rotated at the same speed which could be varied by simply adjusting the disks nearer to or farther from said axis, but it will be observed upon reference to Figure 7 that substantially one half only of each disk —36— and —36'— is adapted to engage the driving disk —27—, the remaining half of each disk being cut away to avoid contact with the driving disk and that the semi-circular contacting portions of the driven disks are reversely arranged so as to alternately engage and release opposite faces of the driving disk, it being understood that the contacting portion of each disk is slightly greater than a semi-circle to assure positive contact of each before the breaking of contact of the other.

That is, the disks —36— and —36'— are alternately driven a half revolution by alternate contact with the adjacent sides of the continuous rotating driving disk —27— and, through the medium of the gears —25—, effecting a continuous rotation of the shaft —30— and pointer supporting shafts —16—.

It is now clear that by making the ratio of the gears —37— and —38— two to one, and by causing the disk —36— to contact with the disk —27— through only half of its circumference, the pointers —15— will be rotated one complete revolution for each half revolution of the shaft —30— and that the interval of time through which the pointers make one complete revolution may be materially varied by simply shifting the disk —36— axially to contact with the adjacent side of the driving disk —27— at different distances from the axis of said driving disk.

Another important advantage in the use of the two driven disks —36— and —36'— alternately engaging opposite sides of the same

driving disk —27— is that the pointers —15— may be caused to move through successive revolutions at different speeds, each revolution of the pointers around the dial indicating the period of "Stop" for the vehicles on one street and the same period of "Go" on the cross street, and inasmuch as the disks —36— and —36'— are adjustable axially, independently of each other, they may be set at different distances from the axis of the driving disk —27— under which conditions the driven disk farther from the axis of the driving disk would cause the pointers —15— to be moved through one revolution faster or in a shorter time than the driven disk which is nearer the axis of the driving disk.

For example, if the disk —36— is farthest from the axis of the driving disk —27— it would be rotated one half revolution at a certain speed which would cause all of the pointers —15— to rotate through a full revolution while the disk —36— is traveling through a half revolution, whereupon the disk —36— breaks contact with the driving disk —27— by presenting its shorter radius thereto.

At the end of this complete revolution of the pointers —15— around their respective dials, the disk —36'— will have been brought into contact with the driving member —27— and will be rotated a half turn thereby before breaking contact therewith, thereby causing the rotation of the shaft —30— to be continued in the same direction through the medium of the gears —35— but at a slower speed resulting in a slower motion of the pointers and consequent longer interval of time in making the next complete revolution, these operations being repeated in the same relative periods while the disks —36— and —36'— remain in the same relative positions with reference to the axis of the driving disk.

Any suitable means may be provided for shifting the friction disk —36— axially and in this instance consists of an upright rod —39— movable through an opening in the bottom of the case —3— and having its upper end extended through the bearing —32— and into the tubular shaft —30— where it is connected to a cross pin —40— which is movable in lengthwise slots —41— in opposite sides of the shaft —30— and thereby serves to spline the disk —36— on the shaft —30— to cause those parts to rotate in unison in addition to its function of attaching the rod —39— to the disk whereby the axial movement of the rod will impart similar movement to the disk.

The lower end of the rod —39—, Figure 3 extends downwardly into the column —2— to approximately the level of the door —4— thereon where it is guided in a suitable bracket —42— on the interior of said column and is provided with a toothed rack —43—.

A horizontal shaft —4— is journaled in

a suitable bracket —45— within and upon the interior of the column —2— and is provided with a pinion —46— meshing with the toothed rack —43— of the rod —39— at approximately the level of the door —4—, said shaft having one end facing the door angular in cross section for receiving a suitable key or crank arm not shown, but by which the shaft —44— and its pinion —46— may be rotated to move the rod —39— axially for the purpose of shifting the disk —36— axially or radially across the face of the driving disk —27— and thereby changing the speed of rotation or time interval of each complete revolution of the pointers —15— as may be desired.

Suitable means is also provided for shifting the disk —36— axially and for this purpose an upright rod —39— is extended through the bearing —32— into the tubular shaft —31— and is attached at its upper end to a cross pin —40— which is secured to the hub of the disk —36— and is movable vertically in lengthwise slots —41— in opposite sides of the shaft —31— thereby connecting the disk —36— to the shaft to rotate therewith and also permitting axial adjustment of said disk by vertical movement of the rod —39—.

The lower end of this rod —39—, Figures 2 and 4, is provided with a toothed rack —43— meshing with the pinion —46— which in turn is secured to a horizontal shaft —48—.

This shaft —48— is journaled in suitable brackets —49— on the bottom —9— of the case —3— and is provided with a spiral gear —50— meshing with a similar spiral gear gear —50— on the upper end of an upright shaft —51— which extends downwardly through an opening in the bottom —9— of a case —3— into the column —2— and has its lower end journaled in a bracket —42— on the interior of said column and provided with a spiral gear —52— meshing with a similar spiral gear —53— on a horizontal shaft —54—, the latter being journaled in the bracket —42— in approximately the horizontal plane of the door —4— and like the shaft —44— has one end facing the door angular in cross section for the reception of a key or other suitable device not shown, by which the shaft may be rotated for imparting rotary motion to the shaft —51— and thereby rotating the shaft —48— to reciprocate the rod —39— axially for shifting the disk —36— radially of the driving disk —27—, the object of which is to cause the pointers to rotate at the same or different speed than that produced by the disk —36—.

Suitable means is provided for holding the disks —36— and —36— in their adjusted positions and for this purpose is provided a pawl —55— for engaging the teeth of the pinion —46— while the shaft —54— is pro-

vided with a ratchet wheel —56— engaged by a pawl —57—, both of said pawls being preferably of the spring type to permit them to ride over the teeth when the corresponding shafts are rotated by hand, but are of sufficient tension to hold said shafts against rotation when the disks are adjusted to the desired positions.

Current may be supported from any suitable source of electric energy for operating the motor —19— and for energizing the several lamps "R" and "G" and —18— and the bell —14—, and for this purpose, we have shown in Figure 9, a main line circuit —A— as supplying current through a conductor —a— and brush —a'— to a conducting sleeve —60— which is mounted on the shaft —30— to rotate therewith but is insulated therefrom by insulation —61—.

Substantially one half of the upper end of the sleeve —60— is cut away to form a semi-circular conducting segment, the remainder of the circle in the same horizontal plane being filled in with the insulator —61— said sleeve being secured to the shaft —30— in such manner that the semi-circular conducting segment at the upper end thereof will be at the same side of the axis as the semi-circular contacting side of the friction disk —36— while the semi-circular insulated portion will correspond to the cut away side of the same disk.

Suitable brushes —62— and —62'— are arranged at diametrically opposite sides of the conducting sleeve —60— in the horizontal plane of the semi-circular segment thereof, so as to contact therewith and are set so that the advancing end of the segment will begin to contact with one of the brushes as —62— at about the same time that the advancing end of the semi-circular contact side of one of the disks as —36— begins to contact with the adjacent side of the driving disk —27— at which time the other brush as —62'— will begin to contact with the semi-circular portion of the insulation —61— thereby energizing all of the lamps which may then be connected in the circuit closed by the contact of the segment with the brush as —62—.

In the diagram, the upper groups of lamps "R" and "G" correspond to those which are located within the case —3— while the lower group represents those in the pedestal —1— and it will be observed that when the semi-circular conducting segment of the sleeve —60— is in contact with the brush —62—, the lower and upper lamps "R" of both groups facing in opposite directions along one street and the opposite side lamps "G" of both groups facing in opposite directions along a cross street will be simultaneously energized while the semi-circular contacting side of the disk as —36— remains in contact with and is driven by the driving disk —27— during which the contact brush —62— re-

mains in contact with the conducting segment of the sleeve —60— and energizes the lamps referred to while the pointers —15— are making one complete revolution, the remaining lamps of both groups being de-energized during the same period by reason of the contact of the brush —62'— with the insulation —61—.

For example, while the brush —62— is in contact with the semi-circular segment of the sleeve —60—, current will be supplied through wire "b" to a bus wire "c" and thence through branches "d" and "d'" to the red lights "R" of both groups for one street and the green lights "G" of both groups for the cross street while the pointers are being rotated one complete revolution by the disk —36—.

On the other hand, just before the contact side of the disk —36— breaks contact with the driving disk —27—, the disk —36'— will make contact therewith at which time, the semi-circular conducting segment of the sleeve —60— will have broken contact with the brush —62— and made contact with the brush —62'— thereby de-energizing the lamps previously energized and causing the energizing of the remaining lamps of both groups through a second bus wire "c'" and its branch wires "e" and "e'" during the next half revolution of the disks —36— and —36'— and next complete revolution of the pointers —15— thus completing the cycle of energizing of the lamps for both streets after which the operations will be repeated in the manner described.

In devices of this character it is desirable to operate an audible signal announcing to the traffic that a change of signals is about to take place and for this purpose is provided the electric bell annunciator —14— which is also controlled electrically by a part of the same switch member —60— through the medium of a brush —f— and wire —f'— leading therefrom to the bell.

As shown in Figure 11, the conducting sleeve —60— is provided at its lower end with diametrically opposite extensions —g— adapted to successively contact with the brush —f— as the sleeve is rotated, said extensions being preferably alined axially with the ends of the semi-circular segment of the sleeve —60— so as to close the bell circuit for a relatively short period just before the trailing end of said segment breaks contact with each of the brushes —62— and —62'— or just before the completion of each revolution of the pointers —15— around their respective dials at which time the change of visual signals in both groups of lamps is made, and the bell circuit is broken to de-energize the bell and simultaneously energize the desired "Stop" and "Go" signals while the disks —36— and —36'— are making the

next half revolution and the pointers are making their next complete revolution.

In order that the pointers may be visible, at night they are provided with suitable electric incandescent lamps —18— to which current is supplied from the said wire —a— through another bus wire —h— and branch wires —i— so that these lamps may be continuously energized while the apparatus is in use.

The motor —19— may be electrically connected across the main circuit —A— as diagrammatically shown in Figure 9 and provided with a switch —19'— for controlling the same, and mechanisms actuated thereby, and if desired, the bus wire —h— may also be provided with a switch —h'— by which the lights to the pointer lamps may also be controlled as desired.

As shown in Figures 4 and 6, the outer ends of the pointer shafts or spindles —16— are provided with collars —70— to rotate therewith, each collar being provided with a pair of contact brushes —71— for engaging conducting rings —73— which are mounted on an insulating sleeve —75— secured to the adjacent bearings —17— said conducting rings being electrically connected in the branch circuits —i— shown diagrammatically in Figure 9.

Operation

The motor —19— being driven at constant speed, it is evident that the pointers —15— will be moved around their respective dials a complete revolution within a pre-determined interval of time of say, one minute, which movement will be at all times visible to the traffic along crossing streets so that the traveling public may know by the movement of the pointers approximately the times of "Stop" and "Go" on both streets.

The light signals are for the purpose of indicating the "Stop" and "Go" period to the traffic on both crossing streets. For example, when the pointers approach their zero positions, the red lights —R— facing in opposite directions along one street and the green lights —G— facing in opposite directions along the other street will be energized to indicate "Stop" to the traffic along the first named street and permit it to "Go" along the other street the lights remaining energized during one complete revolution of the pointers from its zero or starting positions, and at the end of that complete revolution, the other sets of lamps will be energized during the next succeeding revolution of the pointers, these operations being repeated as long as desired.

On the other hand, if it becomes necessary to change the duration of each complete revolution of the pointers it is simply necessary to adjust the disks —36— and —36'— axially or radially with relation to the driving disk —27—.

—27— or these disks —36— and —36'— may be adjusted to different planes to cause the pointers to travel through one complete revolution in one period of time and through the 5 next complete revolution in a different period of time all of which renders the apparatus very flexible and adaptable for all traffic conditions without special attention on the part of the attendant, except to see that 10 the various parts are adjusted for the proper time interval for maintaining visual signals according to the conditions of traffic at the junction of the streets at which the device is usually located, it being understood that immediately preceding each successive revolution 15 of the pointers, from their zero positions, the annunciator —14— will be automatically operated to indicate to the traffic the coming change in signal display which enables the 20 public to be better prepared for instant "Stop" or "Go" movements.

We claim:

1. In a traffic signal, a dial, a pointer movable around the dial, a motor, means for transmitting motion from the motor to the pointer including means adjustable at will for causing the pointer to move through successive revolutions at different speeds, a "Stop" signal and a "Go" signal, and means for alternately energizing said signals at each revolution of the pointer.

2. In a traffic signal, a dial, a pointer movable around the dial, a motor, means for transmitting motion from the motor to the pointer including means adjustable at will for automatically changing the speed of movement of the pointer at the end of each revolution, a "Stop" signal and a "Go" signal, and means for alternately energizing said signals at each 30 revolution of the pointer.

3. In a traffic signal, a dial, a pointer movable around the dial, a rotary driving member, a rotary driven member, means for transmitting motion from the driven member to 45 the pointer devices actuated by the driving member for alternately transmitting motion to the driven member first at one speed and then at a different speed, a "Stop" signal and a "Go" signal, and means for alternately energizing said signals at each revolution of the pointer.

4. In a traffic signal, a pointer movable around the dial, a motor, a rotary friction disk, means for transmitting motion from the 55 motor to said disk, rotary shafts at opposite sides of the disk, means for transmitting motion from one of said shafts to the pointer, means for transmitting motion from one shaft to the other friction disks movable axially on said shafts and alternately engaging the first named disk for driving their respective shafts, a "Stop" signal and a "Go" signal, and means for alternately energizing said signals at each revolution of the pointer.

5. In a traffic regulator, a Stop-signal and

a Go-signal, means including a rotary member for alternately operating said signals, and means for causing said member to travel rotarily a certain distance at one speed to operate one signal and an approximately equal 70 distance at a different speed to operate the other signal.

6. In a traffic regulator, a "Stop" signal and a "Go" signal, means including a rotary member for alternately operating said signals, and 75 means for causing said member to travel rotarily a certain distance at one speed to operate one signal and an approximately equal distance at the same or at a different speed to 80 operate the other signal.

7. In a traffic signal, a dial, a pointer movable around the dial, a rotary driving member, rotary driven members having limited portions thereof movable alternately into driving engagement with the driving member during each revolution of said driven members, so that when one driven member is engaged with the driving member the other driven member will be out of engagement with said driving member, means for alternately moving said rotary members into engagement with said driving member, means for transmitting motion from said driven members to the pointer, and means for moving the driven members toward and from the 90 axis of the driving member for varying the speeds of rotation of said driven members and the pointer actuated thereby.

8. In a traffic signal, a dial, a pointer movable around the dial, a rotary driving friction disk, means for rotating said disk at a constant speed, rotary driven disks having means for alternately engaging opposite faces of the driving disk and adjustable radially thereof for varying their speed of rotation, means for transmitting rotary motion from the driven disks to the pointer, and means for adjusting said driven disks axially independently of each other, each driven disk having means for alternately making and breaking 100 contact with the driving disk during each revolution of said driven disk.

9. In a mechanism of the class described having a plurality of electrical signalling devices to be energized, the combination of 115 a plurality of electric conductors operatively connected with said signalling devices, a rotative circuit-controller member, movable electric contacts operatively connected with and adapted to be moved by said rotative circuit-controller member into and out of contact with said first-mentioned electric conductors in predetermined order, for making and breaking corresponding electric circuits in predetermined order, means for connecting 120 said movable contacts with a source of electric supply, and means for driving said rotative circuit-controller member, said driving means including means for varying the speed of rotation of the rotative circuit-controller 130

member in a part of a continuous revolution relatively to the speed of movement of the same in another part of such revolution, for controlling the duration of signals.

- 5 10. In a mechanism of the class described having electrical signalling devices to be energized, the combination of a plurality of electric conductors operatively connected with said signalling devices, a rotative circuit-controller member, electric contacts on and movable with said rotative circuit-controller member into and out of electrical contact with said electrical conductors in predetermined order, for making and breaking 15 corresponding electric circuits in predetermined order, said movable contacts being adapted to be connected with a source of electric supply, and means for driving said rotative electric controller member, said driving means including means for rotating said rotative member, and means for varying the speed of rotation of such rotative circuit-controller member in a part of its rotative movement relatively to the speed of rotation of 20 the same in another part of such rotative movement, for controlling the duration of signals.

11. In a mechanism of the class described having electric signalling devices to be energized, the combination of a plurality of electric conductors operatively connected with such signalling devices, a rotative circuit-controller member, electric contacts on and movable with said rotative circuit-controller member into and out of contact with said electric conductors in predetermined order, for making and breaking corresponding electric circuits in predetermined order, said movable contacts being adapted to be connected 35 with a source of electric supply, and driving mechanism operatively connected with said rotative circuit-controller member, said driving mechanism including means for rotating said rotative circuit-controller member normally at progressively varying speeds in different parts of each continuous revolution, and comprising means for varying the speed of rotation of said rotative circuit-controller member in a part of a revolution relatively 40 to the speed of rotation of the same in another part of such revolution, for controlling the duration of signals.

12. In a mechanism of the class described, having a plurality of electrical signalling devices, the combination of a plurality of electric conductors operatively connected with said signalling devices, a rotative circuit-controller member, means for rotatively supporting said circuit controller member, a plurality of electric contacts on and movable with said rotative circuit-controller member into and out of contact with said electric conductors in predetermined order, means for connecting the movable contacts 55 with a source of electric supply, and driv-

ing mechanism operatively connected with said rotative circuit-controller member, said driving mechanism including means for varying the speed of rotation of the rotative circuit-controller member in different parts of the revolution of the same for controlling the duration of the periods of contact, between said movable contacts respectively and the corresponding electric conductors, to control the duration of various signals.

13. In a mechanism of the class described, having a plurality of electrical signalling devices, the combination of a plurality of electric conductors connected with said signalling devices, a rotative circuit-controlling member, a plurality of electric contacts on and movable with said rotative circuit-controller member into and out of contact with said electric conductors in predetermined order, for making and breaking electric circuits for controlling said signalling devices, and driving mechanism operatively connected with said rotative circuit controller member, for rotating the same, said driving mechanism including a constant speed motor, and motor-driven variable gearing operatively connected with and forming an operative connection between the motor and said rotative circuit-controller member, and acting to automatically vary the speed of rotation of said rotative circuit-controller member relatively to the speed of the motor, for controlling the time relation between various signals.

14. In a mechanism of the class described, having a plurality of electrical signalling devices, the combination of a plurality of electric conductors operatively connected with said signalling devices, a rotative circuit-controller member adapted to be connected with a source of electric supply, means for rotatively supporting said circuit-controller member, a plurality of electric contacts connected with and adapted to be moved by said rotative circuit-controller member into and out of contact with said electric conductors in predetermined order, for making and breaking electric circuits for controlling said signalling devices, and driving mechanism operatively connected with said rotative circuit-controller member, said driving mechanism including a motor, and means operatively connected with and forming an operative connection between said motor and said rotative circuit-controller member, and acting to automatically vary the speed of rotation of the latter during different parts of each revolution of the same, for controlling the time relation between and the duration of various signals.

15. In a mechanism of the class described having a plurality of electrical lamps, the combination of a rotative electrically conductive drum member, means for rotatively supporting said drum member, means for

- connecting said drum member with a source of electric supply, a series of segmental electric contacts on said drum, a series of stationary electric conductors connected with said lamps and each located adjacent to the path of movement of and adapted to be engaged by a corresponding segmental contact on said drum, and driving mechanism for rotating said drum, said driving mechanism comprising a constant speed motor provided with a motor shaft, and connecting means forming a variable speed connection between said motor shaft and said drum, said connecting means including means for varying the speed of the drum during different parts of each revolution of the same, whereby the time and the duration of the period of lighting the various lamps may be controlled.
16. In a mechanism of the class described, having a plurality of electric lamps, the combination of a rotative electrically conductive drum, means for rotatively supporting said drum, means for connecting said drum with a source of electric supply, a series of segmental electric contacts on said drum, a series of stationary electric conductors electrically connected with said lamps and each located adjacent to the path of movement of and adapted to be engaged and disengaged by a corresponding segmental contact on said drum, and driving mechanism for rotating said drum, said driving mechanism comprising a constant speed motor provided with an armature shaft, and variable speed connecting gear mechanism operatively connected with and forming a connection between said armature shaft and drum, said connecting gear mechanism including means for varying the speed of the drum during different parts of each revolution of the same, whereby the time relation between the duration of various signals may be controlled.
17. In a mechanism of the class described, having a plurality of electric lamps to be intermittently lighted, the combination of a plurality of stationary electric conductors each connected with a corresponding lamp and adapted to form a part of an electric circuit, a rotative circuit-controller member, a plurality of electric contacts on said rotative circuit-controller member and each adapted to be moved by the latter into and out of contact with a corresponding stationary electric conductor, for making and breaking a corresponding electric circuit with which such stationary conductor is connected, means for connecting said movable contacts with a source of electric supply, and driving mechanism comprising a constant speed motor, for rotating said rotative circuit-controlling member, and motor-driven means for varying the relative speed of rotation of said circuit-controller member during different parts of each revolution of the same while maintain-
- ing the time for such complete revolution constant and unchanged, for automatically controlling the time of lighting the respective lamps and the duration of the periods of time during which the respective lamps continue lighted.
18. A switching mechanism comprising a motor, a plurality of switches, switch operating means driven by said motor for opening and closing said switches in a predetermined desired sequence, and common adjusting means included in said switch operating means for varying the time relation of operation between some of said switches and simultaneously with such adjustment varying the relative time of operation of another of said switches to maintain the desired sequence of operation.
19. A switching mechanism comprising a motor, three switches, switch operating means driven by said motor for opening and closing said switches in a predetermined desired sequence, one switch being opened and closed twice for each opening and closing of the other two switches and common means for adjusting the time relation between the operation of said last mentioned switches, and simultaneously adjusting the time of operation of said first mentioned switch to maintain the desired sequence of operation.
20. A switching mechanism comprising a motor, a pair of switches, means driven by said motor for substantially simultaneously opening one of said switches and closing the other and vice versa, a third switch, means driven by said motor for opening and closing said third switch in a predetermined time relation with each corresponding operation of said other switches, and a common adjusting means for adjusting the relative duration of closure between said pair of switches and the time of operation of said third switch to maintain the said predetermined time relation.
- In witness whereof we have hereunto set our hands this 9th day of December, 1922.
- JOHN H. WALRATH.
KARL SCHWARTZ.
